UNITED STATES PATENT OFFICE.

VINCENT M. MONTINGER, OF PITTSFIELD, MASSACHUSETTS, ASSIGNOR TO GENERAL ELECTRIC COMPANY, A CORPORATION OF NEW YORK.

DECORATIVE LIGHTING OUTFIT.

Application filed April 22, 1922. Serial No. 556,086.

The present invention relates to decorative lighting and more especially to electric lighting of Christmas trees and the like.

Many attempts have been made heretofore

5 to put upon the market electric lighting outfit for Christmas tree decoration, but on account of their unreliable and unsatisfactory performance they have failed to displace the old-fashioned tallow or wax taper from its 10 long established position, although its hazardous character is well known.

In lighting a Christmas tree, it is required that there be a multitude of bright spots rather than a high degree of illumination, 15 and in consequence thereof only very small lamps may be employed for that purpose. Small lamps have short filaments and correspondingly low resistivity. Fifteen volt lamps are the largest size deemed satisfactory for this particular use. The ordinary dwelling house electric lighting current is 20 very generally supplied at about 120 volts and is accordingly unsuited for the direct use of small lamps.

25 One of the most commonly adopted expedients for operating miniature lamps from an ordinary house circuit is to arrange a number of such lamps in series between the high and low potential wires of the house 30 circuit. It has been the practice to group the fifteen volt lamps together in series of eight, and to provide each outfit with one or more such groups.

It is well known that the failure of any 35 one lamp in a series arrangement interrupts the flow of current in that circuit, and in consequence all other lamps in the series fail to operate, or, according to the catch phrase, one out all out. Relatively few users had 40 the skill or patience to test out such a series circuit to locate the cause of trouble, and even when one was possessed of the necessary skill and patience to make the requisite renewal the delay and interruption caused 45 thereby often spoiled or so seriously marred some festive occasion that the outfit was liable to be condemned to the waste heap after a single attempt to use it.

The object of my invention is to provide 50 an improved Christmas tree lighting outfit, in which the several lamps are so arranged that each is entirely independent of the operation of every other lamp, in which the trunk wires and the various branch wires 55 are connected and arranged to follow the

natural tree structure, and in which the joints between the various wires are compact and esthetic in appearance and highly efficient electrically and mechanically.

The invention is shown in the accompanying drawings, in which Fig. 1 is an outline of a Christmas tree with one form of my lighting outfit applied thereto; Fig. 2 is a full sized elevation of a moulded union about a wire joint; Fig. 3 is a longitudinal section, 60 and Fig. 4 is a central transverse section of the same.

As shown in Fig. 1, the main or trunk conductor 1, which is double flexible wire with braided insulation, is designed to extend upwardly along the trunk of the Christmas tree, and at different levels has branch conductors 2 which are truncated or varied in length somewhat in accordance with the variation in lengths of tree limbs at different levels. At the ends of each branch conductor and at the top end of the main conductor, there are sockets 3 for the reception of small or miniature lamps 4.

In order that the conductors may withstand the severe usage to which an outfit of this character is subjected and also to care for the esthetic demands made of such a device, I make the joints 5 between trunk line conductor and the branch conductors as follows: The several conductors have at their points of union short sections of the braided insulation 6 stripped therefrom and each pair of wires separated by a fibre disk 7 passed between the positive and negative 70 wires of the trunk and branch conductors. The insulation 8 of the individual wires is removed from short sections at the points of crossing and a drop of solder 9 applied to each crossing. About the severed ends of 75 the braided insulation 6, the bared wires, and the disk 7, is molded under pressure a mass of insulating compound 10. This provides a permanent union of neat and esthetic appearance, thoroughly insulating 80 the conductors operating under difference of potential, effectively uniting together the severed ends of the braided insulation about 85 the wires, and providing a rigid encasement 90 for the soldered joints so that mechanical 95 stresses imposed upon any of the wires cannot operate to break the electrical connection between branch and trunk line wires.

In the arrangement shown, it will be observed that there are twenty-one lamps all 100 105 110

2
connected in multiple relation and with the same difference in potential existing throughout the system. Since the lamps for this particular service are practically restricted to fifteen volts, it is necessary to supply the electric power to the system at that voltage.

In order to employ the ordinary house current to operate the Christmas tree system, I have designed a step down transformer 11 adapted to stand on the floor back of or concealed by the tree with one coil connected by a flexible conductor 12 to an ordinary base outlet 13, while the other coil is equipped with terminals 14 to which the flexible trunk conductor of the system is connected.

What I claim as new and desire to secure by Letters Patent of the United States, is,—

20 1. An electrical connection comprising a double wire trunk conductor, double wire branch conductors crossing said trunk con-

ductors and with wires of like polarity electrically connected at said crossing, insulating means disposed between the wires of unlike polarity at said crossings, and insulating compound molded about said crossed conductors and insulating means.

2. An electrical connection comprising a trunk conductor composed of two insulated wires having thereon braided coverings separated by bare sections, branch conductors of like construction having lamp sockets at their ends and disposed transversely of the trunk conductor with the wires joined at the bare sections, insulating disks disposed between the wires of opposite potential at the points of intersection, and insulating compound moulded about the ends of the braided covering, the wires and said disks.

In witness whereof, I have hereunto set my hand this 18th day of April, 1922.

VINCENT M. MONTSINGER.
